[57] CLAIM

The ornamental design for a playground equipment for children, as shown and described.

DESCRIPTION

FIG. 1 is a front elevational view of a playground equipment for children showing our new design;

FIG. 2 is a rear elevational view;

FIG. 3 is a right side elevational view;

FIG. 4 is an enlarged fragmented top perspective view;

FIG. 5 is an enlarged fragmented interior perspective view; and,

FIG. 6 is an enlarged fragmented top front perspective view.

The broken line showing is for illustrative purposes only and forms no part of the claimed design.
